(57) CLAIM

The ornamental design for a curtain, as shown and described.

DESCRIPTION

FIG. 1 is a front isometric view of a curtain showing my new design, the curtain being shown in an extended position;

FIG. 2 is a front elevational view thereof;

FIG. 3 is a rear elevational view thereof;

FIG. 4 is a top view thereof;

FIG. 5 is a bottom view thereof;

FIG. 6 is a left side view thereof, the right side view being a mirror image of FIG. 6; and,

FIG. 7 is a front isometric view of the curtain depicted in FIG. 1, shown in a partially folded position.

The rings and the pole are shown in broken lines for illustration purposes only and form no part of the claimed design.
